PACKING AND MERCHANDISING
CONTAINER

Carl H. Steinbiss, San Francisco, Calif., assignor
to Lyons-Magnus, Incorporated, San Francisco,
Calif., a corporation of Delaware

Application July 22, 1938, Serial No. 220,760

4 Claims. (Cl. 229—34)

The present invention relates to a packing and merchandising container, and more particularly to a novel packing and display carton formed from a relatively simple blank.

A primary object of the present invention resides in the provision of a novel combined packing and display carton formed in relatively simple manner from a blank as of cardboard or the like, the construction being such that the carton is effectively locked in assembled position and cannot readily come apart.

A further object of the present invention resides in the provision of a novel and relatively simple blank scored along predetermined lines to facilitate the formation of a carton particularly suitable for the merchandising of confections and the like.

Another object of the present invention resides in providing a novel carton for confections or the like formed by simple folding operations with novel means for securing the box in its final folded form without the use of adhesives or complicated interfitting notches.

A further object of the present invention resides in providing a novel carton for confections or the like with a display opening formed by complementary formations provided by the blank.

Another object of the present invention resides in forming a novel combined display and packaging carton having a display opening from a blank having complementary formations designed to provide the opening so as to effect a saving in material by reason of the elimination of a panel having the opening cut therein.

A further object of the present invention resides in providing a carton wherein the ends are formed by overlapping, interfolded flaps designed to automatically lock the carton in its final folded conformation.

Other objects will appear as the description proceeds in connection with the appended claims and attached drawings, wherein:

Figure 1 is a pictorial view of a preferred manner of using the cartons of the present invention.

Figure 2 is a plan view of a preferred form of blank from which the individual carton of the present invention is formed.

Figure 3 is a plan view showing the blank of Figure 2 partially folded and just prior to the folding and interlocking of the end structures.

Figure 4 is a longitudinal sectional view through a folded carton having division members in place to provide separate compartments and illustrating the various steps in folding the end structures in dot and dash lines.

Figure 5 is a fragmental sectional view illustrating a modified manner of interlocking the sloping end of the carton.

Figures 6 and 7 are elevational views of the partitioning members used to form the several compartments in the carton, the dot and dash lines illustrating the blanks from which the partitioning members are formed.

Figure 8 is a plan view of a carton filled with a product such as glacé fruit and having a "Cellophane" wrapper or the like for enclosing the carton and covering the display opening, and

Figure 9 is a sectional view of line 9—9 of Figure 8.

With continued reference to the drawings wherein like reference numerals are employed to designate the same parts throughout the several figures and with particular reference to Figures 2 to 7 inclusive, 10 generally designates a blank used to form the carton of the present invention.

Blank 10 is preferably formed of relatively light paper-board, cardboard or the like, and is cut from a large sheet of such material. Blank 10 is cut and scored, as shown in dot and dash lines, in a single operation to provide a body or back panel 11, a pair of longitudinally extending side panels 12 having squared ends defined by scored lines 13, and irregularly shaped ends providing short squared portions 14 and angular portions formed by scored lines 15. The longitudinal edges formed by scored lines 16 of panels 12 are formed as narrow longitudinal border panels 17 extending from the point of intersection 18 of lines 16 and lines 15 toward the squared ends. Panels 17 are of uniform width from point 18 to point 19 where they curve outwardly to form elongated flaps 21, one edge of each flap forming an extension of line 13.

Attached to panels 12 along lines 13 are longitudinal extending flaps 24 of a width equal to that of panels 12. At their opposite ends, panels 12 are provided with flaps 25 which are attached to panels 12 along lines 15. Flaps 25 preferably extend in a direction normal to that of lines 15. Flaps 25 adjacent their free ends are provided with transverse slits 26 extending partway thereacross for a purpose to be presently described.

Back panel 11 is defined by longitudinal scored lines 27 and transverse scored lines 28 and 29. Attached to panel 11 along line 28 is an end panel 30, border panel 31, and flaps 32 and 33. Scored lines 34, 35 and 36 and edge 37 define panel 31 and flaps 32 and 33. Panels 30 and 31 are preferably of a length equal to the width of panel 11 and flaps 32 and 33 are shorter by a distance d .

equal to or slightly less than the width of panels 11. Slits 38 separate panels 30 and 31 from flaps 24.

Attached to panel 11 along scored line 29 is a relatively narrow end panel 39, a relatively wide end border panel 41 and a flap 42 divided by a scored line 43. Scored lines 29, 44, 45 and edge 46 define panels 39 and 41 and flap 42. Panels 39 and 41 and flap 42 are preferably equal in length to the width of panel 11.

The carton 50 of the present invention is formed by folding blank 10 in the following manner:

Panels 12 are folded upwardly along fold lines 27 so that panels 12 and 17 and flaps 21, 24 and 25 are disposed in a plane normal to the plane of panel 11. Panels 17 are then folded inwardly along fold lines 16 to dispose border panels 17 and flaps 21 in a plane parallel to and above panel 11 as illustrated in Figures 3 and 4. Flaps 24 are then folded inwardly along fold lines 13 to close the left-hand end of carton 50 as illustrated in Figure 3. Flaps 25 are then folded inwardly along fold lines 15 and the slits 26 interlocked as shown in Figure 3 to prevent the side panels 12 and attached border panels 17 and flaps 24 from unfolding along fold lines 21. These folding operations result in a partially folded carton such as that illustrated in Figure 3.

The end portions of carton 50 are now folded in the following manner. The several panel flaps forming flap F¹ are folded upwardly along fold line 28 so as to dispose end panel 30 in overlapping relation to flaps 24. This folding operation places panel 31 and flap portions 32 and 33 in position A as shown in dot and dash lines in Figure 4.

The flap F¹ is then folded inwardly along fold line 34 to dispose panel 31 in engagement with the top of flaps 21 and the ends of border panels 17 as shown in Figure 4. This folding operation places flaps 32 and 33 in position B as illustrated in dot and dash lines in Figure 4. Flap F¹ is then folded upwardly along fold line 36 to place flap 33 in dot and dash line position C illustrated in Figure 4. With flaps 32 and 33 disposed in this last mentioned position, the flap F¹ is folded downwardly around fold line 35 until flap 32 is disposed beneath flaps 21 and flap 33 is disposed in abutting relation to flaps 24 on the side opposite that engaged by panel 29. This last mentioned position of flaps 32 and 33 is the final position and is illustrated in solid lines at the left-hand end of Figure 4.

This folding operation causes flaps 24 to be interlocked between panel 29 and flap 33 and flaps 21 to be interlocked between panel 31 and flap 32. Edge 37 of flap 33 in this final folded position engages the inner surface of panel 11 and locks the end structure in folded position in such a manner that it is impossible for the left-hand end of the carton to become accidentally disengaged and also provides a structure that is relatively difficult to purposely unfold.

The opposite end of carton 50 is folded in the following manner. End flap F² is folded upwardly along fold line 29 to dispose panel 39 in a vertical position closing the lowermost portion of the tapered end of carton 50 and disposing flap F² in position D illustrated in dot and dash lines in Figure 4. Flap F² is then folded toward the opposite end of carton 50 along fold line 44 to place top panel 41 in overlying relation to the top surface of flaps 25 and flap 42 in the dot and dash line position E illustrated in Figure 4. Flap 75

42 is then folded downwardly along fold line 45 and around the upper edges of flaps 25 so as to place flap 42 underneath flaps 25 with edge 46 in engagement with the inner surface of panel 11.

5 In order that end flap F² may be interlocked in this position, the length of flap 42 is preferably slightly longer than the distance from the upper edges of flaps 25 to the surface of panel 11 measured along the sloping under surface of flaps 25. 10 It will be clear, therefore, that flap 42 must be designed to bow slightly in order to assume its final position under flaps 25. To this end, fold line 43 permits a slight downward bowing of flap 42.

15 Since end flap F² is preferably of the same width as panel 11 it is necessary to provide some means for permitting the insertion of flap 42 into its final position. The necessary space is provided at 51 between the end edges 52 of panels 20 17 and the upper edges 53 of flaps 25. Space 51, due to the angle between ends 52 and the edges 53 of flaps 25 (see Figure 2) is automatically formed as blank 10 is folded as heretofore described.

25 Since panels 17, 30, and 41 are relatively narrow with respect to the length and width of back panel 11, the folding operation just described automatically provides a display opening 54 (see Figures 4, 8 and 9) without the necessity of cutting any material from the blank.

30 While end flap F² may be folded as heretofore described, a modified method of folding this flap is illustrated in Figure 5. In this form of the invention, flap F² is folded in the manner heretofore described until it reaches position E. At this time, the end 42a of flap 42 is folded upwardly along fold line 43 and flap 42 is then folded downwardly along fold line 45 and around edges 53 of flaps 25 so as to dispose flap 42 underneath flaps 25 with edge 46 of portion 42a in engagement with the inner surface of panel 11 forming a vertical wall. This alternate method of folding flap F² also provides an interlock to prevent accidental unfolding of flap F².

35 With the carton in its final folded position as illustrated in solid lines in Figure 4, the carton may be filled with a confection such as glacé fruit or any desired material. While such a confection may be placed in a carton 50 having the one large compartment, it is preferable to provide partitioning members to divide the carton into several compartments. To this end, partitioning members 55 and 56 illustrated in Figure 4 are provided. Member 55 is formed from a flat paperboard blank 57, shown in dot and dash lines in Figure 6, by folding flap 58 upwardly into a plane normal to flap 59 and folding flap 61 inwardly into abutting engagement with the ends of flap 58.

40 Member 56 is formed from a similar blank 62, shown in dot and dash lines in Figure 7, by folding flap 63 upwardly into a plane normal to flap 64 and folding flaps 65 inwardly into abutting engagement with the ends of flap 63.

45 Members 55 and 56 are positioned in carton 50 through display opening 54 and the flaps 61 and 65 extend along side panels 12 into abutting engagement with flap 33 at the squared end of the box. Since flaps 65 are approximately twice as long as flaps 61 the carton is divided into three approximately equal sized compartments. These compartments are then filled in any suitable manner.

50 After carton 50 is filled with a confection illustrated at 67 in Figures 8 and 9, the carton is

preferably wrapped in a "Cellophane" wrapper 68 which is sealed in any desired manner to provide a sanitary package and a covering for display opening 54. While material such as "Cellophane" is preferred, it is understood that other transparent materials on the market may be employed.

Referring to Figure 8, it will be seen that the carton of the present invention, due to the cooperation of panels 17, 31 and 41 and wrapper 68, provides a highly effective display package so that the contents of the carton may be viewed through the "Cellophane" wrapper 68. The completed carton provides an unusually strong package since the multiple plies at the end tend to impart rigidity to the box. As a consequence, the cartons may be readily stacked one upon the other with very little danger of crushing the contents or upon the squared ends for display purposes as shown in Figure 1.

Referring to Figure 1 wherein a preferred manner of displaying carton 50 is disclosed, a shallow open topped box-like paper-board receptacle 70 having a suitable decorative front panel 71 and a relatively tall back panel 72 is provided for receiving cartons 50. Panel 72 is preferably provided with suitable descriptive printing 73 and a space 74 for the insertion of the price of the article. Cartons 50 are placed on their squared ends with the opening 54 facing panel 71 to exhibit the confection above the top of panel 71. With the cartons arranged in this manner, panels 41 with the name of the manufacturer if desired and the name of the particular confection contained in the box are disposed so that they may be viewed from the front or from above the receptacle 70. Preferably receptacle 70 is designed to receive a dozen of the cartons 50 disposed in three rows of four cartons each. The cartons are arranged one behind the other in the rows so that as one carton is removed the other cartons will be in position to be properly displayed to the customers.

While the above mentioned manner of displaying cartons 50 may be resorted to, printing on the panel 41 may be reversed, that is to say, turned up-side-down, and the box laid flat upon back panel 71 on the shelf of a show case so that panel 41 may be viewed from the front of the show case or through the usual transparent top. Accordingly, cartons 50 of the present invention, adapt themselves for display purposes in such a manner that the customer does not have to stoop or place himself in an uncomfortable position in order to view the name of the goods or manufacturer on the box.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A blank for forming a confection or like carton capable of being secured in final form without the use of adhesives or locking means comprising a main body portion, a projecting portion at each end, having substantially parallel scored lines where each projecting portion may be folded into panels forming the ends of the car-

ton, a projecting side panel portion at each side for forming the sides of the carton; a diagonally disposed flap at the matching ends of each side panel portion adapted to be folded transversely of said body portion to form a sloping top end portion overhanging said end of said body portion and having cooperating slits for locking said flaps and side panels in proper position; a narrow projecting portion at the free side of each of said second mentioned projecting portions for forming top side portions overhanging said body portion; a coplanar right angularly extending flap at the end of each narrow projecting portion adjacent the opposite ends of said second mentioned projecting portions adapted to be folded transversely of said body portion to form a top end portion overhanging the other end of said body portion; and a flap at said same opposite end of each of said second mentioned projecting portions adapted to be folded transversely of said body portion to form an end wall at that end of said body portion, said first mentioned projecting portions being adapted to be folded at said scored lines to form connected panels engaging both the exterior and the interior of said top end portions and said end wall respectively, and having end portions engaging the main body portion for locking the blank in its final folded formation.

2. A confection or like carton comprising a back panel; side panels; relatively narrow side border panels at the top edge of said side panels, said narrow border panels having transversely extending flaps at one end thereof, the free ends of which abut to form a top end border panel at one end of said back panel; transversely extending flaps at said one end of said side panels forming an end wall at the respective end of said back panel; transversely extending flaps at the opposite ends of said side panels forming a combined top and end border panel at the other end of said back panel, said last-mentioned flaps having slits whereby said flaps may be interlocked to retain said side panels and said end wall flaps in a plane normal to said back panel; and longitudinally extending flaps at the respective ends of said back panel, having fold lines defining connected panels which pass over and under said transverse flaps at the opposite ends of the back panel respectively to abut the opposite surfaces of said transversely extending flaps, and the free transversely extending edges of said longitudinal flaps abutting said back panel for retaining said end wall and the adjacent top end border panel in proper position and for retaining said slotted flaps in cooperating engagement.

3. A confection or like carton comprising a back panel; side panels having sloping edges adjacent one end and squared edges at the other ends; marginal top panels forming a display opening and a sloping end, formed by a pair of transversely folded flaps carried by said sloping edges of said side panels and having a lower edge slightly spaced above said back panel and a higher edge spaced above said back panel a greater distance, said flaps including slits therein in interlocking engagement to prevent unfolding of said side panels and said top panels; a flap folded upwardly to close the space between said slightly spaced edges and said back panel, and having a portion overlying the top surface of said pair of transversely folded flaps in contacting relationship therewith to provide a sloping name display panel, and a portion folded around said upper edges of said pair of flaps and underlying

the said pair of flaps in contacting relationship, said last-mentioned portion being of a length sufficient to have its free edge engage said back panel and having a transverse scored line to permit a slight downward bowing of said portion between the parts in engagement with the underside of said pair of flaps and the part engaged with the inner surface of said back panel, to prevent unfolding of said end.

4. The combination defined in claim 3 wherein a squared end is formed on the other end of the carton by a pair of vertically disposed flaps having their ends in abutting engagement to close said squared end; a pair of horizontally disposed flaps in the plane of the top edge of said vertical flaps providing an inwardly extending overhanging marginal formation along the whole of said end; a flap carried by the adjacent end of said

5 back panel and including a vertically extending portion engaging the outer surface of said vertical flaps; a horizontally extending portion engaging the upper surface of said horizontal flaps to provide an end marginal panel, a second horizontally extending portion engaging the under surface of said horizontal flaps for interlocking said flaps between said marginal panel and said last-mentioned portion; and a vertically extending portion engaging the inner surface of said vertical flaps and having its transverse edge in engagement with the inner surface of said back panel whereby said vertical panel is gripped between said horizontal portions and said back panel to prevent disassembly of said horizontal flaps and unfolding of said end.

CARL H. STEINBISS.
